UNITED STATES PATENT OFFICE.

RUDOLPH M. HUNTER, OF PHILADELPHIA, PENNSYLVANIA, ASSIGNOR TO SCOTT PAPER COMPANY, A CORPORATION OF PENNSYLVANIA.

SANITARY COVER FOR TOILET-SEATS.

1,121,015.

Specification of Letters Patent. Patented Dec. 15, 1914.

Application filed September 26, 1912. Serial No. 722,527.

To all whom it may concern:

Be it known that I, RUDOLPH M. HUNTER, citizen of the United States, and resident of Philadelphia, county of Philadelphia, and State of Pennsylvania, have invented 5 an Improvement in Sanitary Covers for Toilet-Seats, of which the following is a specification.

The object of my invention is to provide 10 a sanitary covering for toilet seats adapted for public service, the covering being so applied that it may be readily renewed.

My object is further, to provide such covering by the employment of soft paper in 15 roll form, which may be provided without requiring special machinery or dies, thereby enabling my improvement to be employed at low cost.

My invention consists in combining the 20 seat with suitable holders and guides and employing therewith a web or webs of paper in roll form carried by the holder and guided about the guides so as to cover the edges of the seat aperture.

More specifically considered, my invention 25 in its preferred form, may be best practised by using a double web roll, the webs of which are simultaneously employed as a seat covering as more fully described hereinafter.

My invention also comprehends details of 30 construction which, together with the features above specified, will be better understood by reference to the accompanying drawings, in which:

Figure 1 is a plan view of a seat with my improved sanitary covering applied thereto; Fig. 2 is a side elevation of the same; Fig. 3 is a plan view of my improvements in modified form. Fig. 4 is a front elevation and Fig. 5 a side elevation of the modified form of my invention shown in Fig. 3; Fig. 6 is a plan view of one of the rear guides of the modified construction; and Fig. 7 illustrates the folds made in the 45 paper web thereby; and Fig. 8 is a side elevation showing my preferred roll of two webs.

2 is the usual seat, which may be provided with the aperture 4 and may be 50 hinged at 3. To the front portion of the seat I secure a slotted guide 6 and below it, I provide a holder 5 for supporting the paper roll 9. At the rear portions of the seat and at each side thereof, I provide 55 oblique guides 7 and 8 about which the

paper webs are guided. The roll 9 comprises two webs 10 and 11 rolled together into a single roll and so as to unwind together. These webs are drawn upward through the slotted guide 6 and then separated, web 10 being guided about the guides 7 and web 11 guided about guide 8. The free ends 13 of these webs are crossed as at 14 and drawn under the opposite webs 10 and 11 so as to be held down by them. The 60 guides 7 and 8 are obliquely arranged with respect to each other and to the slotted guide 6, so as to cause the paper webs to fold at the proper angles to provide the bounding edges 12 and 14 to cover the edges of 65 the opening 4, as will be readily understood by reference to Fig. 1.

In the modification shown in Fig. 3, the 70 guides 7^a and 8^a are formed of flat plates instead of bent wires to provide double angular edges about which the web is bent, so that the angle between the parts 12 and 14 of the web is not as acute as in the construction of Fig. 1. It is to be understood that I do not restrict myself as to the form of 75 the guides for the webs.

The webs 10 and 11 may be perforated at 80 intervals sufficient to provide a length of web necessary to provide the parts 12 and 14, the extreme ends 13 being provided by 85 such perforated portions. It is also desirable to employ thin tissue paper for the webs so that when detached, they may be thrown into the toilet and discharged as 90 waste.

I have shown my invention as employing 95 a roll of two webs, but it will be understood that if desired a single web may be employed, and when so used may be guided about both guides 7 and 8 and returned to 100 the guide 6, as this would be merely a matter of threading or guiding the web about the guides and would not change the operative feature of providing a sanitary covering by use of a web and guides. I therefore do not restrict myself in this respect, though I prefer the employment of the 105 double webs as enabling the use of lighter and narrower webs while providing a multiple covering at the rear portion of the seat.

Having now described my invention, what I claim as new and desire to secure by Letters Patent, is:—

1. In a sanitary toilet seat covering, the 110 seat, combined with guides at front and rear

portion thereof and arranged at angles to each other, a compound roll of paper having two webs guided about the guides and having their side edges overlapping the seat opening.

2. In a sanitary toilet seat covering, the seat, combined with guides at front and rear portion thereof and arranged at angles to each other, a compound roll of paper having two webs guided about the guides and having their side edges overlapping the seat opening the free ends of the respective webs being arranged under the opposite webs whereby said free ends are held down and the webs provide a plurality of paper plies at the rear portion of the seat.

3. In a sanitary toilet seat covering, the seat, combined with a roll holder at the front of the seat and two obliquely arranged

guides at the rear portion of the seat, and a compound roll of paper comprising two webs rolled upon each other and said webs guided apart and thence about the guides and finally folded to rest over each other to form a plurality of plies, and with the edges of the webs overlapping the seat opening.

4. In a sanitary toilet covering, the seat, combined with a compound roll of paper consisting of two webs rolled upon each other, a support for the compound roll of paper, and guides on the seat about which the webs are guided to separate them.

In testimony of which invention, I hereunto set my hand.

R. M. HUNTER.
